COIN SELECTING APPARATUS

Merral P. Haverstick, St. Louis, Mo., assignor of one-half to The Vendo Company, Kansas City, Mo., and one-half to Coin Acceptors, Inc., St. Louis, Mo., both corporations of Missouri

Filed Feb. 6, 1961, Ser. No. 37,308

6 Claims. (Cl. 194—102)

This invention relates to coin operated mechanism and especially to a coin receiving unit having means for separating good coins from spurious ones and without jamming of the unit that would require operator attention before the coin operated mechanism could be caused to operate through another cycle.

Coin operated vending machines have become increasingly popular in recent years with the number of units as well as the types of merchandise dispensed, increasing at a rapid rate. Most of these vending machines are operated by the customer either depositing coins of pre-selected value in the machine, or in the alternative, inserting certain coins followed by manual operation of selector buttons, levers or similar vend mechanisms. Because of the fact that the vending machines are many times located in unattended areas and furthermore because of the fact that constant surveillance is not maintained over the machines, attempts have been made to obtain products from the machines without deposit of genuine coins. Counterfeit coins, slugs, metallic discs and other similar objects have been used in efforts to actuate the vend mechanism and for this reason, complex and highly refined coin selecting apparatus has been developed over a period of years, for separating spurious coins from genuine coins regardless of the type of counterfeit coin which is deposited in the vending machine. The coin selecting units have conventionally employed various means for testing the authenticity of the coin as to size, weight and materials from which the objects are made, but some difficulty has heretofore been experienced with respect to detecting slugs or discs of slightly smaller than proper diameter and which have physical properties very similar to that of a genuine coin.

Most coin selecting apparatus utilize cradle structure pivotally mounted substantially in the zone of juncture of a coin rejecting pathway therebeneath, and a coin accepting pathway adjacent the coin rejecting pathway, and with the cradle being provided with spaced projections thereon adapted to support a coin of a particular denomination so that the cradle is pivoted about the axis of rotation thereof to divert the coin into the coin accepting pathway. The spaced projections on the cradle structure, however, are sufficiently spaced to pass therethrough coins of other denominations which have smaller diameters. The coins passing between the cradle projections are directed into the coin rejecting pathway. Thus the cradle principle is suitable for separating coins or discs having relatively wide diameter differences such as nickels, dimes and quarters, but such cradle is not capable of being utilized to separate coins or discs of slightly smaller than required diameter, from coins of predetermined, particular diameter. The spacing between the cradle projections has not proved satisfactory as a means for rejecting slugs or discs of a slightly smaller diameter than a proper coin for the reason that the slightly smaller coin would have a tendency to become wedged between the cradle projections and could not be cleared from the mechanism upon operation of the scavenger. Consequently, the cradle projections are purposely designed to be spaced very appreciably closer than the minimum diameter of the particular denomination of coin to be normally supported therebetween. It is basic that

2

the center of gravity of a coin carried by the cradle projections is to one side of the axis of rotation of the cradle so that the latter will be rotated in a manner to divert the coin on the projections, into the coin accepting pathway.

It is therefore the most important object of the present invention to provide coin selecting apparatus as described including novel means for preventing rotation of a cradle as defined above when the same is supporting a coin of 10 slightly smaller than proper diameter whereby the coin will be ejected from the coin receiving mechanism upon manual actuation by the customer of the reject lever. In this respect, it is to be pointed out that a further important object of the invention is to provide coin selecting apparatus as referred to above wherein the means for preventing rotation of the cradle when the latter is supporting a coin of slightly smaller than proper diameter, cooperates with and engages the cradle to preclude rotation thereof to divert such coin into the coin accepting 20 pathway.

A still further important object of the invention is to provide coin selecting apparatus wherein the means for preventing rotation of the cradle unless the latter is supporting a coin of predetermined diameter, includes a 25 swingable lever having means thereon projecting into the coin receiving pathway and which is engaged by the coin while the latter is carried by the cradle projections, so that during swinging of the cradle under the weight of the coin deposited thereon, such coin shifts the projection 30 on the adjacent check lever to move the latter into disposition clearing the cradle whereby the latter may divert the genuine coin into the coin accepting pathway.

Other important objects including the simplicity of the present check lever and the effectiveness thereof without 35 jamming of the machine, will become obvious or be explained in greater detail as the following specification progresses.

In the drawings:

FIGURE 1 is a front elevational view of coin selecting 40 apparatus embodying the preferred concepts of the present invention and illustrating a coin in dotted line on the selector cradle forming a part of the apparatus;

FIG. 2 is a vertical sectional view taken on the line

2—2 of FIG. 1 and looking in the direction of the arrows; FIG. 3 is a horizontal sectional view taken on the line 45 3—3 of FIG. 1 and looking downwardly;

FIG. 4 is a fragmentary, elevational view of the inside portion of the swingable gate mounted on the frame of the coin selecting apparatus;

FIG. 5 is a fragmentary, front elevational view similar to FIG. 1 and illustrating the disposition of the coin and the parts moved thereby during passage of the coin from the coin receiving pathway into the coin accepting pathway;

FIG. 6 is a fragmentary, front elevational view similar to FIG. 5 but illustrating the coin in another position thereof as the same is being diverted into the coin accepting pathway; and

FIG. 7 is an exploded view of the coin selecting cradle and the associated selector member preventing rotation of the cradle when an undersized coin is carried thereby.

The coin selecting apparatus broadly designated 10 in the drawings includes a main frame 12 having a normally 55 vertically disposed, rectangular wall 14 provided with a pair of integral, outwardly extending, opposed, vertical side walls 16 and 18 projecting outwardly from the normally front face of wall 14. A pair of integral ears 20 and 22 projecting inwardly from wall 18, receive an elongated pin 24 which mounts a main gate 26 and a secondary gate 28 which are rotatable about the vertical axis of pin 24. The gate 26 includes a generally rectangular

lar plate portion 30 having a mounting extension 32 on the end thereof proximal to wall 18 as well as a pair of outwardly projecting, integral legs 34 and 36 which are positioned adjacent the outer opposed faces of respective ears 20 and 22 and rotatably receiving pin 24 so that gate 26 may swing toward and away from the proximal face of wall 14. The coil spring 38 surrounding pin 24 between ears 20 and 22, has a pair of opposed coiled portions 38a and 38b, and an integral, outwardly projecting, central portion 38c disposed to engage the inner face of wall 18. The outer rectilinear extremity 38d of coil spring 38 and projecting outwardly from portion 38b thereof, engages a cross portion 40 integral with opposed legs 41 and 43 of secondary gate 28, while the extremity 38e of spring 38 and integral with portion 38a of the latter, engages the outer face of rectangular portion 30 of gate 26 to force the latter toward wall 14. As best shown in FIG. 1, legs 41 and 43 of gate 28 are located between ears 20 and 22 and are pivotal about pin 24. The main section 42 of gate 28 carries a transversely L-shaped coin clearing member 44 provided with an inwardly extending outer leg portion 46 which projects away from secondary gate 28 and thereby toward wall 14. The plate portion 30 of main gate 26 is provided with an elongated slot 48 therein for clearing leg portion 46 of member 44. The rectangular boss portion 50 of gate 28 and integral with main section 42 thereof, houses a pair of permanent magnets 52 which test the coins for magnetic properties and thereby trap all objects deposited in apparatus 10 which are sufficiently attracted by magnets 52 to be held thereby.

A pair of pins 54 and 56 secured to the plate portion 30 of gate 26 adjacent the upper left-hand corner thereof viewing FIG. 1 are located in horizontally spaced relationship to present a coin receiving opening of predetermined width therebetween, it being pointed out that pins 54 and 56 extend toward and releasably engage the inner face of wall 14 to thereby maintain gate 26 in predetermined spaced relationship to wall 14. Pins 54 and 56 are preferably positioned to pass a coin of required diameter therebetween, but at a distance insufficient to pass a larger coin such as a half dollar for example, if selector apparatus 10 is designed for operation by quarters. The upper margin of plate portion 30 of gate 26 adjacent side wall 16 is flared outwardly at 58 to cause coins deposited in apparatus 10 to be directed downwardly through the space between pins 54 and 56.

A coin testing cradle broadly designated 60 is pivotally mounted on plate portion 30 immediately below pins 54 and 56 as shown in FIG. 1, with cradle 60 including a main, generally circular portion 62 provided with a pair of opposed legs 64 and 66 at approximately right angles with respect to each other. Inwardly extending projections 68 and 70 are integral with corresponding legs 64 and 66, with plate portion 30 of gate 26 having a pair of opposed upper and lower arcuate slots 72 and 74 receiving projections 68 and 70 respectively. The central circular portion 62 of cradle 60 has a tubular boss 76 thereon which extends outwardly from cradle 60 and thereby provides means for mounting the latter on a pin 78 carried by plate portion 30 of gate 26 and extending forwardly therefrom. A C-clip 80 on the outer extremity of pin 78 extending through central portion 62 of cradle 60 as well as tubular boss portion 76 thereof, releasably maintains cradle 60 on gate 26 but permits free rotation thereof in an arcuate path of travel limited by the length of opposed arcuate slots 72 and 74 receiving projections 68 and 70 respectively. The central portion 62 of cradle 60 also has a pair of arcuate margins 82 and 84 normally facing toward member 44 and interrupted by a shoulder 86 provided with a surface in generally radial relationship to the axis of pin 78. A counterweight 88 on the outer face of central portion 62 of cradle 60 is eccentric with respect to the axis of pin 78 and thereby biases cradle 60 in a counterclockwise direction viewing FIG. 1

whereby projections 68 and 70 are normally in proximity to the ends 90 and 92 respectively of slots 72 and 74.

In addition to the novel configuration of cradle 60 and particularly the margins 82 and 84 thereof in conjunction with shoulder 86, the additional unique element of the present invention is the undersize coin check lever or member 94 which is mounted on plate portion 30 of gate 26 in proximal relationship to cradle 60. The central portion 96 of member 94 is provided with an integral tubular boss 99 on the rear face thereof which pivotally receives a pin 98 carried by and extending outwardly from plate portion 30 of gate 26. The outwardly projecting extension 100 integral with central portion 96 serves to bias member 94 in a counterclockwise direction as shown in FIG. 1, whereby the inwardly extending projection 102 of central portion 96 of member 94 is normally maintained in proximal relationship to margin 84 of cradle 60 in a position causing shoulder 86 to normally engage projection 102 of member 94 as cradle 60 is rotated in a clockwise direction. Upwardly extending, generally L-shaped leg 104 integral with the upper margin of central portion 96 of member 94, has an inwardly extending projection 106 thereon with plate portion 30 of gate 26 being provided with an elongated slot 108 therein for clearing projection 106 to permit check member 94 to pivot about the axis of pin 98. It is to be noted that a C-clip 110 on the outer extremity of pin 98 and engaging the outer surface of central section 96 maintains boss 99 against the outer face of plate portion 30.

Main plate portion 30 of gate 26 is provided with a trapezoidal shaped component 112 thereon adjacent the lower margin 114 of the same and having an upwardly facing, inclined surface 116 presenting a coin runway and cooperating with the inner surface of plate portion 30 and the proximal surface of wall 14 to present a coin accepting pathway in proximal relationship to the magnets 52 carried by secondary gate 28.

In order to permit coins to be cleared from the cradle 60 if the same are oversize or undersize, a manually operable lever 118 is pivotally mounted on the rear face of wall 14 opposed to gates 26 and 28 and is provided with an integral, inclined cam surface 120 thereon which receives a projection 122 integral with the inner face of plate portion 30 of gate 26 whereby during downward movement of lever 118, the projection 122 slides along inclined surface 120 to thereby force gate 26 outwardly against the action of coil spring 38. A leaf spring 124 carried by the pivot pin for lever 118 and engaging the upper, outwardly projecting portion of the latter as well as an outwardly projecting nut 126 on wall 14, normally biases lever 118 into the uppermost position thereof whereby gate 26 is in proximal disposition with respect to the inner face of wall 14.

During swinging movement of gate 26 with respect to frame 12, secondary gate 28 does not move therewith, because of boss 128 on main section 42 of gate 28 which extends through an opening 130 in plate portion 30 of gate 26 and thereby engages the inner face of wall 14, as best shown in FIG. 3.

In operation, apparatus 10 is positioned within coin controlled mechanism forming a part of a vending machine or the like, and thus the coin receiving opening in the upper part of frame 12 defined by flared portion 58 of gate 26 as well as the proximal portion of wall 14 and opposed pins 54 and 56, is disposed to face upwardly in direct alignment with a coin entrance chute. As the coin 132 gravitates between pins 54 and 56 and thereby into the coin receiving pathway, such coin initially engages projection 68 on cradle 60 and is thereby directed toward the projection 70 on leg 66 of cradle 60. Assuming that coin 132 is of proper dimensions for the particular coin selecting apparatus 10, the coin will be supported by both of the projections 68 and 70 in bridging relationship thereto in a location substantially as shown in FIG. 1. In as-

much as the center of gravity of coin 132 is to the right of the axis of shaft 78, viewing FIG. 1, cradle 60 is rotated in a clockwise direction against the influence of counterweight 88 whereby the coin 132 is diverted toward the coin accepting pathway presented by the inner face 5 of wall 14, the opposed faces of gates 26 and 28 and the upwardly facing surface 116 of runway component 112.

As soon as cradle 60 has rotated through a relatively short arc, the outer margin of the coin engages the projection 106 on member 94 as shown in FIG. 5, thereby 10 causing member 94 to swing in a clockwise direction and moving projection 106 on central portion 96 of member 94 away from margin 86 of cradle 60. The coin 132 shifts leg 104 and thereby member 94 through a sufficient arc to cause projection 106 to clear shoulder 86 of circular portion 62 of cradle 60 (FIG. 6) whereby the cradle 15 may rotate through a sufficient arc to direct the coin 132 onto the runway surface 116 of component 112. After coin 132 has left the cradle 60, the latter is returned to the initial position thereof under the action of counterweight 88 and the extension 100 of member 94 returns the latter to the location illustrated in FIG. 1.

In the case of an undersize coin, even though the same is cradled between projections 68 and 70, the cradle 60 is not permitted to move through a sufficient arc to divert the coin onto runway 112, because of the fact that the coin will not engage projection 106 in a manner to shift member 94 through an arc to cause projection 106 to clear shoulder 86 on central circular portion 62 of cradle 60.

The check member 94 also prevents cradle 60 from being rotated by an undersize coin of insufficient diameter to be cradled on projections 68 and 70 and which in certain instances, could otherwise occur. For example, if apparatus 10 is designed for selecting quarters and a dime 35 is dropped into the coin receiving passage, such coin could drop downwardly with sufficient force to engage the projection 70 of cradle 60 and thereby rotate the latter through an arc to throw the dime into the coin accepting pathway presented by runway component 112. Because 40 a coin of this diameter will not engage the projection 106 on check member 94, the latter will not be permitted to rotate through an arc to clear shoulder 86 and thus preventing rotation of the cradle 60.

As previously noted, it is to be understood that an 45 undersize coin carried by cradle 60 will be rejected from apparatus 10 upon manual actuation of lever 118 by virtue of the fact that gate 26 moves outwardly to cause the projections 68 and 70 to release the coin inasmuch as the leg portion 46 of member 44 contacts the proximal surface of the coin and prevents the latter from moving along with projections 68 and 70 during outward movement of cradle 60 on plate portion 30 of gate 26. By virtue of the fact that the undersize coin has not passed through the coin receiving pathway presented by component 112, 55 such undersize coin will be directed to the reject passage of apparatus 10.

Having thus described the invention what is claimed as new and desired to be secured by Letters Patent is:

1. In coin selecting apparatus provided with structure 60 defining a coin receiving pathway, a coin rejecting pathway therebelow, and a coin accepting pathway adjacent said coin rejecting pathway, the combination of:

(a) a cradle adapted to be pivotally disposed substantially at the zone of juncture of said pathways and provided with a pair of spaced projections thereon extending into said coin receiving pathway for testing a coin, said projections being disposed in positions to pass a coin of a substantially smaller than acceptable diameter therebetween and into said coin 70 rejecting pathway, and to receive a coin of approximately proper diameter thereon, said cradle being swingable under the weight of a coin on said projections, in a direction to divert the coin into said coin accepting pathway and having a shoulder there- 75

on normally adjacent said coin accepting pathway; and

(b) a selector member adapted to be pivotally mounted adjacent said cradle and the coin accepting pathway and including an extension engageable with said shoulder on the cradle after the latter has swung a limited distance under the weight of a coin or disc thereon for preventing further rotation of the cradle in said direction through a sufficient arc to divert a coin, if of less than acceptable diameter, into said coin accepting pathway, weight means forming a part of said member disposed to bias the latter into disposition with said extension within the path of travel of said shoulder to preclude substantial rotation of the cradle, and a projection located in a position to be engaged by a coin of proper diameter when the latter is positioned on said cradle projections and with the coin swinging said member projection and thereby the member through a sufficient arc during rotation of the cradle under the weight of said proper diameter coin, to cause the extension on the member to clear said shoulder whereby the coin is diverted from the cradle into said coin accepting pathway.

2. In coin selecting apparatus provided with structure 25 defining an upright coin receiving pathway and a coin testing pathway extending laterally therefrom, the combination of:

(a) a coin test component adapted to be pivotally disposed substantially at the zone of juncture of said pathways for receiving and supporting a coin thereon of a selected denomination, said component being rotatable under the weight of a coin on said component, through an arc sufficient to effect diversion of the coin or disc is of less than acceptable diameter, component being constructed to pass therethrough coins of other denominations having substantially smaller diameters than coins of said selected denomination; and

(b) undersize coin check means engageable with said component after the latter has swung a limited distance under the weight of a coin or disc thereon for preventing further rotation of the cradle through an arc to permit diversion of the coin or disc supported by the component, into the coin testing pathway if the coin or disc is of less than acceptable diameter, said check means being provided with coin or disc operated structure thereon for shifting the check means to a position clearing the component for rotation substantially through said arc, said structure being positioned to be engaged by a coin or disc on the component to effect movement of the latter to said position thereof only by a coin or disc supported by the component of a diameter at least as great as the diameter of a coin of said selected denomination.

3. In coin selecting apparatus provided with structure defining an upright coin receiving pathway, a coin pathway therebelow, and a coin testing pathway extending laterally from said coin receiving pathway, the combination of:

(a) a coin test cradle adapted to be pivotally disposed substantially at the zone of juncture of said pathways and including spaced coin support projections on the same within the path of coins passing downwardly in said coin receiving pathway for receiving and supporting a coin thereon of a selected denomination, said cradle being rotatable under the weight of said coin on the support projections, through an arc sufficient to effect diversion of the coin into said coin testing pathway, said support projections being sufficiently spaced to pass therebetween coins of other denominations having substantially smaller diameters than coins of said selected denomination; and

(b) selector means pivotally disposed adjacent said cradle, said selector means and the cradle having parts thereon movable into interengagement after the

cradle has swung a limited distance under the weight of a coin or disc thereon for preventing further swinging of said cradle under the weight of said coin or disc, if of less than acceptable diameter, through a sufficient arc to permit the coin or disc to be diverted by the cradle into said coin testing pathway, said selector means including an element disposed to be engaged by a coin of said selected denomination when the latter is carried by the projections of said cradle for swinging the selector means through a sufficient arc during pivoting of said cradle to move said part on the selector means into a position clearing said part on the cradle whereby coins of said selected denomination are diverted into said coin testing pathway by said cradle.

4. Coin selecting apparatus as set forth in claim 3 wherein is provided means on said selector means for biasing the latter toward the position thereof whereby the part of said selector means engages the part on said cradle during pivoting movement of the latter when supporting a coin or disc of less than acceptable diameter.

5. Coin selecting apparatus as set forth in claim 3 wherein said element on the selector means comprises a projection extending into the coin receiving pathway adjacent said coin testing pathway and having an edge facing said cradle, said edge lying in an imaginary circle which passes through the coin supporting projections on said cradle and has a diameter substantially equal to the diameter of a coin of said selected denomination.

6. In coin selecting apparatus provided with structure defining an upright coin receiving pathway and a coin testing pathway extending laterally therefrom, the combination of:

(a) a coin test cradle adapted to be pivotally disposed substantially at the zone of juncture of said pathways and including spaced coin support projections on the same within the path of coins passing downwardly

5
10
15
20
25

in said coin receiving pathway for receiving and supporting a coin thereon of a selected denomination, said cradle being rotatable under the weight of said coin on the support projections, through an arc sufficient to effect diversion of the coin into said coin testing pathway, said support projections being sufficiently spaced to pass therebetween coins of other denominations having substantially smaller diameters than coins of said selected denomination; and

(b) undersize coin check means engageable with said cradle after the latter has swung a limited distance under the weight of a coin or disc thereon for preventing further swinging thereof under the weight of said coin or disc if of less than acceptable diameter through a sufficient arc to permit the coin or disc to be diverted into said coin testing pathway, said coin check means including means disposed to be engaged by a coin of said selected denomination when the latter is carried by said projections of the cradle for moving the selector means into disposition permitting the cradle to clear said selector means during pivoting of the cradle whereby a coin of said selected denomination is diverted into said coin testing pathway by said cradle.
